UNITED STATES PATENT OFFICE.

SAMUEL HAUDENSHIELD, OF CARNEGIE, PENNSYLVANIA.

ROTARY ENGINE.

No. 900,013.

Specification of Letters Patent. Patented Sept. 29, 1908.

Application filed April 18, 1907. Serial No. 369,023.

To all whom it may concern:

Be it known that I, SAMUEL HAUDENSHIELD, a citizen of the United States of America, residing at Carnegie, in the county of Allegheny and State of Pennsylvania, have invented certain new and useful Improvements in Rotary Engines, of which the following is a specification, reference being had therein to the accompanying drawing.

10 This invention relates to rotary engines, and the invention has for its object to provide a novel reversible engine from which a maximum amount of efficiency can be obtained, with a minimum expenditure of fuel.

15 My invention aims to provide an engine having an eccentrically mounted revoluble head, provided with a plurality of radially disposed pistons which can be easily and quickly adjusted to compensate for the wear 20 and tear of the pistons without removing the pistons from the engine. In this connection, I have devised a novel packing for the pistons whereby the engine can be economically operated to obtain the highest degree of efficiency from an engine of the above type.

The detail construction entering into my invention will be hereinafter more fully described and then specifically pointed out in the appended claims, and referring to the 30 drawing forming part of this specification, like numerals of reference designate corresponding parts throughout the several views, in which:—

Figure 1 is a longitudinal sectional view of my improved engine, Fig. 2 is a cross sectional view of the detachable plate of the engine, Fig. 3 is an elevation of the same, Fig. 4 is a plan of the steam chest, Figs. 5, 6 and 7 are perspective views of a packing used in 40 connection with the engine, Fig. 8 is an elevation of the revoluble head of the engine, Fig. 9 is a cross sectional view of the same, Fig. 10 is a cross sectional view of the engine, Figs. 11 and 12 are detail views of a packing used 45 in connection with the pistons of the engine, Fig. 13 is a perspective view of one of the pistons of the engine, Fig. 14 is an elevation of one of the piston actuating arms, Fig. 15 is a vertical sectional view of one of the pistons, Fig. 16 is an elevation of a spring used in 50 connection with the packing of the pistons, Fig. 17 is a perspective view of the packing used in connection with the piston, Fig. 18 is an elevation of the engine.

55 To put my invention into practice, I construct my improved engine, of a cylindrical

casing 1 supported upon a base or suitable foundation 2. Upon the top of the casing is formed an enlargement 3 terminating in a steam chest 4, which communicates with the bore 5 or interior of the casing 1, by vertically disposed inlet ports 6—6^a, said ports being arranged in the ends of the enlargement 3. The steam chest 4 is closed by a plate 7, suitable packing 8 being interposed between the plate 7 and the top of the chest 4. Connected with the plate 7 is a steam inlet pipe 9.

Arranged within the steam chest 4 are two slide valves 10, said valves controlling the inlet of steam to the ports 6 and 6^a. The valves are carried by a rod 11 slidably mounted in the steam chest 4 and in a bracket 12 provided therefor in said chest. The outer end of the rod 11 is connected to an operating lever 14 suspended from a bracket 15 carried by the plate 7. The steam chest is provided with a segment-shaped gage 16 for determining the position of the lever 14.

The base or foundation 2 of the engine is provided with two horizontally disposed exhaust ports 17 and 17^a communicating with vertically disposed ports 18. These ports can be connected together by a pipe leading to a suitable point of exhaust. The horizontal exhaust ports 17 and 17^a are formed in the sides of the base 2 and communicate with the bore 5 of the casing 1, said ports communicating with the bore at two points ninety degrees apart. In the ports 17 and 17^a are 90 slidably mounted valves 19, the valve stems 20 of which extend outside of the base 2 and connect with links 21 and 22. The link 21 is connected to the crank arm 23 of a shaft 24, journaled in a bracket 25 carried by the side 95 of the casing 1. The shaft 24 is provided with a crank arm 26, connecting by a rod 27 with the crank arm 28 of a shaft 29 located upon the opposite side of the engine, said shaft being journaled in a bracket 30 carried 100 by the base 2. Connected to the shaft 29 is an operating lever 31, to which the link 22 is connected, said lever being provided with a movable locking pawl 32 adapted to engage in a notched bar 33, carried by the base 2 of 105 the engine.

The valves 10 and 19 are actuated by the levers 14 and 31 respectively to reverse the engine, the ports 6 and 17 being closed when the engine is operated in one direction, as in 110 the direction of the arrow of Fig. 1 of the drawings, while the ports 6^a and 17^a are

closed when the engine is operated in the opposite direction.

The casing 1 is provided with detachable side plates 34, said plates being secured by 5 nuts 35 to stud bolts 36 carried by the edges of the casing 1. The plates are formed with central enlargements 37 upon their outer sides and with seats 38 in their inner sides, said seats carrying tapering annular blocks 39, which are adjusted in their seats by 10 screws 40 and locked therein by screw bolts 41. The object of the tapering annular blocks will presently appear.

Journalized in the enlargements 37 of the 15 plates 34, and transversely of the casing 1, is a drive shaft 42 said shaft being eccentrically arranged with respect to the axis of the casing 1, to support a head 43, mounted concentrically upon the shaft 42, within the casing 20 1. Since the head is of a less diameter than the bore 5 of the casing 1 and is eccentric with relation to said casing, a crescent-shaped compartment is formed between the periphery of the head 43 and the inner sides 25 of the bore 5, this compartment conveying steam from the inlet ports to the exhaust ports.

The head 43 is formed with a web 44 having 30 annular packing grooves 45 formed therein in which packing is located to engage the tapering annular blocks 39 of the plates 34 and form a steam tight connection. The head 43 is provided with radially disposed 35 slots 46 for pistons 47, the confronting outer edges of said slots and the edges of said head being provided with packing grooves 48 and 49 within which suitable packing is arranged to insure a steam-tight connection between the pistons 47 and the outer edges of the slots 40 46, and the edges of the head 43 and the plates 34, respectively.

The pistons 47 are grooved, as at 50 to 45 receive packing strips 51 and 52, the latter being supported by springs 53, arranged in sockets 54 formed in the strips 52 and in the pistons 47. The packing strips 51 are adapted to engage the inner sides of the bore 5, while the packing strips 52 engage the plates 34, during the rotation of the head 43. The 50 springs 53 serve to hold the packing strips 52 in engagement with the plates 34, the upper ends of the strips elevating the packing strips 51 and retaining said strips in engagement with the inner sides of the bore 5 of the casing 55 1. The pistons are provided with depending shanks 55 carrying trunnions 56 for segment-shaped actuating arms 57, said arms being arranged upon both sides of the web 54 of the head 43 and engaging the tapering annular blocks 39 of the engine.

The enlargement 3 of the engine between the inlet ports 6 and 6^a is provided with a 60 recess 58 for a packing block 59, said block being adjusted by screws 60 passing through 65 the sides of the steam chest 4, and engaging

the packing block 59. The packing block is recessed, as at 61, to accommodate a roller 62, said roller bearing against the periphery of the head 43 and being retained in said packing block by packing strips 63, these 70 strips also engaging the periphery of the head 43.

I provide the inner sides of the bore 5 of the casing 1 with grooves 64, said grooves extending from the inlet ports 6 and 6^a to within 75 close proximity to the exhaust ports 17 and 17^a. These grooves, being open to the crescent-shaped compartment, form steam passages which permit of communication between the steam chambers on opposite sides 80 of the piston, and being also in communication with the inlet port, provide means whereby the inlet ports cannot be closed or cut-off by the pistons, so that there is no possibility of the head stopping in such a position as would prevent its being started again 85 as soon as steam is introduced through the inlet port.

The casing 1 is provided with lubricant receptacles 65 for feeding the lubricant to the 90 bore 5 of the casing 1, thus insuring easy rotation of the head 43 within the casing.

Operation: With the valves 10 and 19 in the positions shown in Fig. 1 of the drawings, steam entering the chest 4 passes through the port 6^a and enters the crescent-shaped compartment of the bore 5, where it impinges against the first piston which lies within that portion of the compartment extending between the steam inlet and exhaust ports, thereby causing the piston and head to rotate until the piston passes the port 17^a at which time the steam behind the piston exhausts, but in the mean time another piston has taken steam from the port 6^a. It will thus be observed that the steam traverses practically one-half of the casing 1 before exhausting, thus obtaining full use of the steam before its final escape.

As shown, the annular tapering blocks are 110 arranged with their peripheries concentric with respect to the inner surface of the bore 5 but eccentrically to the shaft 12, therefore, during the propelling of the head 43 by the steam-impelled pistons 47, the pistons will 115 remain in contact with both the inner face of the casing and the periphery of the blocks, the eccentric mounting of the head causing the pistons to have a relative in and out movement within the slots 46.

As the surface of the piston actuating arms wears, the blocks 39 can be moved inwardly, to insure a positive operation of said arms and the pistons 47. This is a distinct feature of my invention to which I attach considerable importance.

It is thought that the operation of my improved engine will be fully understood without further description, and while I have herein disclosed the preferable construction 130

of the engine, I desire it to be understood that such changes in the size, proportion and minor details of construction, as are permissible by the appended claims, may be resorted to without departing from the spirit and scope of the invention.

It will be understood that although I have herein described my engine operating with steam power, any other motive force such as 10 hydraulic, compressed air, or the like may be employed.

What I claim and desire to secure by Letters Patent, is:—

1. In a rotary engine, the combination of a 15 casing having a grooved bore formed therein, a base supporting said casing and having exhaust ports formed therein communicating with said bore, valves movably mounted in said exhaust ports, an enlargement carried 20 by said casing and having inlet ports formed therein, a steam chest carried by said enlargement, slide valves mounted in said chest for controlling said inlet ports, plates carried by said casing, annular tapering blocks adjustably mounted upon the inner side of said 25 plates, a shaft journaled in said plates and blocks, a head carried by said shaft within said casing and arranged eccentrically with relation to the bore thereof, radially disposed 30 pistons movably mounted in said head, piston actuating arms connecting with said pistons and engaging said tapering blocks, packing carried by said pistons, and packing arranged in said enlargement and adapted to 35 engage said head.

2. In a rotary engine, the combination of a casing, a base supporting said casing and having exhaust ports formed therein, valves controlling said ports, said casing having inlet ports formed therein, a steam chest carried by said casing and communicating with said inlet ports, valves located in said chest for controlling said inlet ports, plates carried by the sides of said casing, a shaft journaled 45 in said plates, a head mounted upon said shaft within said casing, radially disposed pistons arranged in said head, piston actuating arms connecting with said pistons upon the sides of said head, packing carried by 50 said pistons, and means carried by the inner sides of said plates for guiding said piston actuating arms and normally maintaining said pistons in engagement with the inner sides of said casing.

3. In a rotary engine, the combination of a casing, having a bore formed therein, a base supporting said casing and having exhaust ports formed therein, an enlargement carried by said casing and having inlet ports 60 formed therein, plates carried by the sides of said casing, a shaft journaled in said plates, a head mounted upon said shaft within said casing, a piston movably mounted in said head, piston actuating arms arranged upon 65 the sides of said head, packing carried by

said pistons, means carried by the inner sides of said plates for guiding said piston actuating arms, and means arranged at one side of said engine for controlling the inlet and exhaust ports thereof.

4. In a rotary engine, the combination of a 70 casing having a bore formed therein, a base supporting said casing and having exhaust ports formed therein, an enlargement carried by said casing and having inlet ports formed therein, plates carried by the sides of said casing, a shaft journaled in said plates, a head mounted upon said shaft, pistons movably mounted in said head, piston actuating arms arranged upon the sides of said head, means 75 arranged upon the inner sides of said plates and engaging said arms for normally holding said pistons in engagement with the inner sides of said casing, and valves for controlling said ports, and reversing said engine.

5. In a rotary engine, the combination of a 80 casing having a bore formed therein, a base supporting said casing and having exhaust ports formed therein, an enlargement carried by said casing and having inlet ports formed 85 therein, plates carried by the sides of said casing, a head eccentrically journaled in said casing, pistons movably mounted in said head, piston actuating arms arranged upon the sides of said head, means carried by the 90 inner sides of said plates for guiding and adjusting said arms, and valves operable from the side of said engine for controlling said ports.

6. In a rotary engine, the combination of a 95 casing having a bore formed therein, a base supporting said casing and having exhaust ports formed therein, an enlargement carried by said casing and having inlet ports formed 100 therein, plates carried by the sides of said casing, a head eccentrically journaled in said casing, pistons movably mounted in said head, piston actuating arms arranged upon the sides of said head, and means carried by 105 the inner sides of said plates for guiding said 110 arms.

7. A rotary engine embodying a casing having inlet and exhaust ports formed therein, plates carried by the sides of said casing, a head eccentrically journaled within said casing, pistons movably mounted in said head, piston actuating arms arranged at the sides of said head and connecting with said pistons, and means adjustably carried by the inner sides of said plate and contacting with 115 said arms for guiding the same.

8. In a rotary engine, the combination with a casing having inlet and exhaust ports and a steam space, of a head mounted eccentrically of said casing, said head having 120 radially-movable pistons, and adjustable means carried by the sides of the casing for controlling the relative movements of the head and pistons.

9. In a rotary engine, the combination 125

with a casing having inlet and exhaust ports and a steam space, of a head mounted eccentrically of said casing, said head having radially-movable pistons, and means carried by the sides of the casing for controlling the relative movements of the head and pistons, said means being adjustable in a manner to take up wear.

10. In a rotary engine, the combination with a casing having inlet and exhaust ports and a steam space, of a head mounted eccentrically of said casing, said head having radially-movable pistons, and tapering blocks carried by the sides of and arranged concentrically of the inner periphery of the casing, said blocks being adjustable laterally of the axis of the casing.

11. In a rotary engine, a piston head having an annular flange on its opposite sides and a plurality of radially-extending slots leading to the periphery of the head and intersecting said flanges to provide segments having bearing faces on their sides and ends, each of said faces having grooves for the reception of a packing.

12. In a rotary engine, a piston head having an annular flange on its opposite sides and a plurality of radially-extending slots leading to the periphery of the head and intersecting said flanges to provide segments having bearing faces on their sides and ends, each of said faces having grooves for the reception of a packing, said grooves being V-shaped in cross-section.

35 13. In a rotary engine, a piston having its outer face and ends provided with sectional packing automatically expansible under

wear, said packing comprising independent members for the face and ends respectively, the face member being expanded by the outward movement of the end members, the end members and the opposing faces of the piston having a relative configuration to prevent movement of the end members in a direction at right angles to the face of the piston.

14. In a rotary engine, a piston having its outer face and ends provided with sectional packing automatically expansible under wear, said packing comprising independent members for the face and ends respectively, the face member being expanded by the expanding movement of the end members, the end members and the opposing faces of the piston having a relative configuration to prevent movement of the end members in a direction at right angles to the face of the piston.

15. In a rotary engine, a piston having its outer face and ends provided with sectional packing automatically expansible under wear, said packing comprising independent members for the face and ends respectively, the piston and the end members having complementary opposing surfaces formed to force said end members laterally during a movement toward the face of the piston, and prevent the end members moving in a direction at right angles to the face of the piston.

In testimony whereof I affix my signature in the presence of two witnesses.

SAMUEL HAUDENSHIELD.
